UNITED STATES PATENT OFFICE.

MARTIN J. SCHUILING, OF GRAND RAPIDS, MICHIGAN.

DESIGN FOR A KITCHEN-CABINET.

46,699.

Specification for Design.

Patented Nov. 24, 1914.

Application filed July 31, 1914. Serial No. 854,402. Term of patent 7 years.

To all whom it may concern:

Be it known that I, MARTIN J. SCHUILING, a citizen of the United States, residing at Grand Rapids, in the county of Kent and State of Michigan, have invented a certain new, original, and ornamental Design for Kitchen-Cabinets, of which the following specification, which, taken in connection with the accompanying drawing, fully discloses the design such that others may understand the same.

In the drawing: The figure shows in perspective the design of my kitchen cabinet.

In its essential features the design comprises an elongated upright casing 1 open at the front and divided by partition 2 into upper and lower compartments. The space below said partition being filled by the drawers 3 and 4 while in the upper portion of the upper compartment a tilting bin 5 is mounted having in its front wall a plurality of transparent members 6, through which the contents of the bin may be seen; the bin

and the drawers 3 and 4 are each provided with a handle 7 as shown. At one side of the casing 1 adjacent the lower end of the bin is mounted the receptacle 8 of the outline and formation shown, in the sides of which are also positioned a plurality of transparent members 9 through which the contents of the receptacle may be seen. The bin 5 is mounted a considerable distance above the partition 2.

This design of kitchen cabinet presents a pleasing and attractive appearance and one that appeals to the eye of the observer.

I claim:

The ornamental design for a kitchen cabinet substantially as shown and described.

In testimony whereof I affix my signature in presence of two witnesses.

MARTIN J. SCHUILING.

Witnesses:

FRANK E. LIVERANCE, Jr.,
HOWARD H. YARRINGTON.
